UNITED STATES PATENT OFFICE.

MELLEN N. BRAY, OF BOSTON, MASSACHUSETTS.

DESIGN FOR A RIVET.

SPECIFICATION forming part of **Design No. 27,639, dated September 14, 1897.**

Application filed December 4, 1896. Serial No. 614,498. Term of patent 14 years.

To all whom it may concern:

Be it known that I, MELLEN N. BRAY, of Boston, in the county of Suffolk and State of Massachusetts, have invented and produced a new and original Design for Rivets, of which the following, taken in connection with the accompanying drawings, is a specification.

Figure 1 of the drawings is a plan of a rivet illustrating my design, and Fig. 2 is a central 10 vertical section of the same.

The leading feature of my design consists in a rivet provided with a tubular cylindrical shank, and a head having a smooth circular outer edge or rim, and an upper surface that is composed of a series of annular beads, and a central circular flat surface, the general contour of said outer surface being curved or convex, and an under surface in the form of an annular flat plane surrounding the shank 20 or attaching member.

In the drawings, II is the rivet-head, the

general outline of the outer surface of which is convex with a smooth circular outer edge and a flat annular inner surface surrounding the shank or attaching member S, which is a 25 hollow cylinder.

The generally convex outer surface of the head II has formed thereon a series of annular beads b, surrounding a central circular flat surface a.

What I claim is—

The design for a rivet substantially as herein shown and described.

In testimony whereof I have signed my name to this specification, in the presence of 35 two subscribing witnesses, on this 2d day of December, A. D. 1896.

MELLEN N. BRAY.

Witnesses:

N. C. LOMBARD,
GEO. E. STROUT.
